United States Patent

Des. 240,461
Patented July 6, 1976

240,461

VISCOUS FAN DRIVE

Wayne K. Leichliter, Rodney H. Detty, and John B. Hill,
Marshall, Mich., assignors to Eaton Corporation

Filed Nov. 18, 1974, Ser. No. 524,441

Term of patent 14 years

Int. Cl. D15—01

U.S. Cl. D77—1 A

FIG. 1 is a perspective view of one side of a viscous fan drive showing our new design.

FIG. 2 is an end elevational view thereof.

FIG. 3 is a perspective view of the other side thereof.

We claim:

The ornamental design for a viscous fan drive, as shown.
